COVER FOR CONTAINERS

Rinsai Maeda, Seattle, Wash.

Application November 13, 1935, Serial No. 49,522

1 Claim. (Cl. 217—62)

This invention relates to covers for crates and containers, and particularly to adjustable sections thereof, and fasteners therefor.

In the transportation and sale of fruit and farm produce, it is generally necessary to remove the entire covers of all forms of containers therefor, in order to view the contents, and see the condition thereof as for passage of such produce across State limits and into public markets.

10 In the use of the ordinary crates, baskets, and other containers, it is customary to nail or otherwise firmly fasten the tops and covers thereof for rigidity and in order to prevent the spilling and loss of such produce.

15 Again when it becomes necessary to inspect the contents such covers must be forcibly removed and generally with tools which damage such covers, and otherwise cause delay and difficulty in reattaching such covers.

20 It is therefore one of the objects of this invention to provide a fixed cover with an adjustable and removable panel over a central window space thereof. In the use whereof the outer edges of the covers may be rigidly attached, and leave 25 such panels to be easily moved to provide suitable inspection of the contents.

Another object is to provide adjustable fasteners, for retaining such panels in closed position, and which may be manually detached to 30 permit the opening of such panels, and the re-fastening thereof, without special tools therefor, and without injury to the fasteners or crates.

With these and other objects that will hereinafter appear, I have illustratively exemplified 35 my invention by the accompanying drawing of which

Figure 1 shows a perspective end view of a crate, with an adjustable panel, and a latch clip for attachment and detachment,

40 Figure 2 shows a perspective side view of the two ends of similar crate with a movable panel, but such panel differently mounted,

Figure 3 shows a sectional fragmentary view of such crates, and a wedge for binding the panel 45 in closed position on a crate,

Figure 4 shows a detail view of one of the latch clips, and means of attaching the same to one end of a panel,

Figure 5 shows a perspective view of a basket 50 form of container, with an attached cover, and an adjustable panel therewith, and latch means for attaching such panel manually,

Figure 6 shows a perspective detail view of a 55 fragment of such basket and an adjustable bail for connection with a latch,

Figure 7 shows a sectional view of a fragment of a basket and panel with a latch and bail and method of connecting the same.

Like numerals on the different figures represent like parts. Number 1 represents the ends of an ordinary fruit crate, 2 the sides thereof, and 3, 3 two outer sections of cover with a relatively narrow window space between the sections. These sections are rigidly attached to the respective ends as by nails or screws 5' driven into the 10 box ends and through the cover section ends and through reinforcing and abutment cleats 5 and spacing bolsters 6. The bolsters are shorter than the width of said sections, and thereby leave the inner edges 3' of the latter which are flexible, 15 free to be raised on an angle into the space 7 above, as seen in Figure 1.

A central cover section or panel 4 is slidably positioned with its outer edges beneath the up-raised edges of the side sections, and normally 20 retained in fixed position thereby, with the ends thereof under the two cleats, during transportation. When necessary for inspection purposes, the operator inserts a finger, or tool, into an aperture 8, provided therefor and for ventilation, 25 and withdraws the panel and views the contents 14. A handle clip 9 may be attached to one end of the panel, for convenience.

On the opposite end of the panel, a latch clip 10 of pliable material is attached, with a point 30 protruding beyond the panel. When the panel is closed, this point is turned upward at right angles and binds against the outer edge of the adjoining abutment cleat and so normally retains the panel in such closed position. For 35 transportation purposes, it is sometimes advisable to insert a wedge 11 into the space between the ends of the panel and the cleats above.

It will be understood that the operator may manually release the clip 10, and the wedge when 40 necessary to slide open the panel for inspection, and again close and attach the panel when inspection is completed.

As the panel sections and covers of such crates and containers are thin and easily split it is 45 necessary that special means for attaching the clips be provided. I have illustrated such means in Figure 4 with prongs 11 extended through and clinched beneath the boards, and shorter outside prongs 12, for preventing the board from 50 splitting.

In Figure 2 an additional latch means for maintaining the panel closed is shown as a nail 13, driven into the end board 1, and bent to provide a movable end latch. In Figure 2 is also 55

illustrated another disposition of the panel, viz. the placing of the same over the inner edges 3' of the side sections. This alternate position may be used when the goods are on display and the 5 panel to be frequently removed, temporarily for purchasers. The panels when positioned either above or beneath the inner edges of the side boards provide rigidity to the closed cover, which is an important factor during transportation.

10 Figures 5, 6 and 7 illustrate the application of the sliding panel to a modified form.

Numerals 15 represents any form of basket for marketing produce, formed of upright staves, and an outside hoop 16 around the top, and a similar hoop 17 inside, the three parts being connected by staples 16' or other suitable means.

A permanent cover is preferably constructed with two courses of thin boards. The lower course of outside boards 18 extend across the 20 top and the intermediate boards terminate with their inner ends 18' spaced apart for an opening 19, through which the contents as 20 may be inspected. The upper course is formed of two outside boards 21, affixed across the lower course 25 and spaced apart wider than the opening between the ends 18'. The inside edges of said boards 21 are sloped to provide a dovetail mortice 21' or guide way, for a movable panel 22. The edges of the latter are formed as a dovetail tenon 30 22' which is slidably mounted in the mortice. A ventilator aperture 8' provides a means also for opening and closing of the panel over the produce 20. The inner ends 18' of the short boards furnish a support for such panel, or movable portion 35 of the cover.

Flexible wire holding bails 23 are provided over the outer hoop 16 as abutments for retaining the panel 22 in closed position. The panel is provided with flexible latch clips 10' at each end 40 thereof and which normally project beyond such ends.

In making the attachments the operator bends the ends of the clips downward, and bends the bails outward, then inserts the clip under the 45 bail as shown in Figure 7.

The bails are then pressed against the hoops 16, and the clip ends turned up over the bail, similar to parts 24' and 25. The said last two parts however are shown as permanent attach-

ments of the side boards 21, by clip 24. The said boards 21 may in many cases be nailed or otherwise more permanently affixed to the retainer. The bails 23, may be adjusted and held in position by bending the inner ends 23' and sliding 5 the same up between the staves and hoops to be there retained by tension provided by the staples 16'.

I am aware that containers have been described with entire covers slidable and removable between the side walls of containers, but such full covers when so removable cannot be rigidly attached to such sidewalls, and so fail to provide necessary rigidity to the container for shipments, and must be fully removed to permit 15 necessary inspection of the goods contained. In my cover, the proper rigidity and containing strength is provided by the major portions of the covers being directly affixed to the walls of the container, thus insuring against damage in trans- 20 portation and assuring no loss of contents, while the narrow central panel for operation over the inspection window in the center, is sufficiently connected to withstand shipments of the goods in safety against loss, and may be easily opened 25 and closed by hand without tools therefor, and provide easy access for inspection of the goods at any time. It is therefore my special construction that I desire to cover by my claim 30 herewith.

Having described my invention, I claim as new:

A container for farm produce comprising a receptacle with the opposite and major side portions of the top thereof covered by fixed boards in relatively narrow spaced relation, the inner edges of such side boards adapted to retain a central panel beneath the same, a relatively narrow central panel with the outer edges thereof slidably connected with the inner edges of such side boards, and adapted to be moved for uncovering produce for inspection, through the space between said boards over the center of such container, spacing bolsters beneath, abutments on the ends of the receptacle for retaining said panel in closed position, and flat pliable clips on the ends of said panels for manual latching contact with such abutments to prevent dislodgement of such panel during transportation. 45

RINSAI MAEDA.
